(57) **CLAIM**

The ornamental design for a fascia lower trim, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a fascia lower trim showing our new design;

FIG. 2 is a front view thereof;

FIG. 3 is a rear view thereof;

FIG. 4 is a left side perspective view thereof, the right side perspective view being a mirror image;

FIG. 5 is top view thereof; and,

FIG. 6 is a bottom view thereof.

1 Claim, 4 Drawing Sheets
(4 of 4 Drawing Sheet(s) Filed in Color)

Related U.S. Application Data
